UNITED STATES PATENT OFFICE.

ANTHONY D. NICHOLS, OF SAN FRANCISCO, CALIFORNIA, AND WILLIAM W. McMAHAN, OF DETROIT, MICHIGAN, ASSIGNS, BY MESNE ASSIGNMENTS, TO UNITED STATES TIRE COMPANY, OF NEW YORK, N. Y., A CORPORATION OF NEW YORK.

DESIGN FOR A RUBBER OR ELASTIC VEHICLE-TIRE.

45,723.

Specification for Design.

Patented May 5, 1914.

Application filed December 20, 1910. Serial No. 598,472. Term of patent 14 years.

To all whom it may concern:

Be it known that we, ANTHONY D. NICHOLS, a citizen of the United States, residing in the city of San Francisco, State of California, and WILLIAM W. McMAHAN, a citizen of the United States, residing in the city of Detroit, State of Michigan, have invented a new, original, and ornamental Design for Rubber or Elastic Vehicle-Tires, of which the following is a specification, reference being had to the accompanying drawing, forming a part thereof.

The figure of the drawing is a perspective

view of a vehicle tire showing our new design.

We claim:

The ornamental design for a rubber or elastic vehicle tire, as shown.

ANTHONY D. NICHOLS.
